UNITED STATES PATENT OFFICE.

WILLIAM F. KENDT, OF BUFFALO, NEW YORK, ASSIGNOR TO GEORGE C. STRAUSS, OF BUFFALO, NEW YORK.

DESIGN FOR A BICYCLE-FRAME.

42,605.

Specification for Design.

Patented June 11, 1912.

Application filed January 2, 1912. Serial No. 669,102. Term of patent 7 years.

To all whom it may concern:

Be it known that I, WILLIAM F. KENDT, a citizen of the United States, residing at Buffalo, in the county of Erie and State of New York, have invented a new, original, and ornamental Design for Bicycle-Frames, of which the following is a specification, reference being had to the accompanying drawing, forming part thereof.

Figure 1 is a side elevation of the bicycle

frame showing my new design. Fig. 2 is a top plan view of the same.

I claim:

The ornamental design for a bicycle frame, as shown.

WILLIAM F. KENDT.
